UNITED STATES PATENT OFFICE.

ERNEST PENBERTHY, OF DETROIT, MICHIGAN, ASSIGNOR TO CHICAGO PNEUMATIC TOOL COMPANY, OF NEW YORK, N. Y., A CORPORATION OF NEW JERSEY.

MOVABLE MOUNT FOR DRILLING MACHINES.

Application filed July 2, 1923. Serial No. 648,859.

This invention relates to apparatus used in mining and in similar operations for advancing a tool toward the work. In particular it relates to improvements in feeding devices such as slide mountings for drilling machines and the like and especially in the movable supports or cradles upon which the machines are mounted and in the means for attaching the machines to the same.

Among the objects of the invention are to provide a simple but strong device of the class described which will permit a sinker type of rock drilling machine to be used as a drifter type, which provides for quick attachment and detachment of such a machine without the necessity of disturbing in any respect the assembly of the parts of the machine and without providing the casing of the machine with special fittings or attachments, to hold the machine against undesirable relative movement when mounted upon the device, and in general to improve prior devices and to render them more efficient, convenient and satisfactory in service.

In order to illustrate the invention, typical species of the genus constituting the invention are shown by way of example in the accompanying drawings, in which:

Fig. 1 is a plan view of a slide mounting embodying the features of the invention;

Fig. 2 is a side elevation on an enlarged scale of the cradle shown in Fig. 1 with a drilling machine mounted thereon, the supporting frame being largely cut away;

Fig. 3 is a right end elevational view of the parts shown in Fig. 2 with the supporting frame in section;

Fig. 4 is a left end elevational view of the parts shown in Fig. 2 with the supporting frame in section;

Fig. 5 is a side elevational view similar to Fig. 2 with the supporting frame entirely omitted and disclosing a modified form of cradle;

Fig. 6 is a plan view of the cradle shown in Fig. 5 with the through bolts and handle yoke of a drilling machine indicated by dot and dash lines;

Fig. 7 is an end elevational view of Fig. 5 with the cylinder and through bolts of the drilling machine in section; and

Figs. 8 and 9 are elevational views simi-

lar to Fig. 7 showing modified attaching means at the front of the cradle.

The embodiments of the invention chosen for the purpose of illustration are designed and adapted for use with any of the commonly used makes of the hand type of rock drilling machines ordinarily used in sinker operations to adapt the same for use in drifting. Such a machine is illustrated in Figs. 2 and 5 and indicated by the reference character A. This type of drill is ordinarily provided with through or side belts B which extend through projections on the sides of the drill casing, such as the perforated lugs C, and serve to retain the parts of the drill in assembled relationship, the heads B' of the through bolts in the form shown being in abutting contact with the handle yoke D of the drill. Guide projections or lugs E on the drill cylinder cooperate with the bolts B to retain the parts of the drilling machine in alignment. Since the drilling machine itself forms no part of the present invention, further description thereof is omitted.

The supporting frame of the feeding device illustrated in Fig. 1 and partially in Figs. 2, 3 and 4 is of conventional form comprising spaced parallelly disposed side members 10 with longitudinal guide grooves 11 having end members 12 supporting in bearings 13 the feed screw 14 extending between side members 10 and which may be rotated by suitable means such as the crank handle 15.

The form of the slide or cradle proper 16 illustrated in Figs. 1 to 5 inclusive upon which the drilling machine is mounted for movement longitudinally of the supporting frame above described, is provided with laterally extended flanges 17 which fit into the guide grooves 11 of members 10. A threaded nut or bushing 18 secured in a bore 19 in a depending extension 20 of the cradle, serves as the means whereby the cradle is moved when the feed screw 14 is rotated, the nut 18 being held in place by an enlarged head 18' thereon at one end and a lock nut 18² at the other.

The cradle serves as the movable support for the drilling machine and is provided adjacent its ends with means for securing the machine in place. At its front or left end cradle 16 has a loop or strap 21 of a

size to permit the forward end of the drilling machine to be passed therethrough. This loop 21 as shown and by preference is integral with the cradle. At the rear, 5 the cradle is provided with transversely aligned upwardly and outwardly diverging arms 22 adapted to be disposed between arms D' of the handle yoke D of the drilling machine when the latter is in position upon the cradle. The forward faces of the arms 22 are provided with recesses or sockets 23 in which the heads B' of the through bolts B are adapted to seat and to be positively retained therein by suitable 15 means such as movable clamping jaws in the form of offset heads 24 of bolts 25 mounted in vertical bores in the arms 22. By setting up the nuts 26 on bolts 25, the clamping jaws 24 will clamp the through bolt heads B' against the fixed clamping jaws formed by the bottoms of the recesses 23.

When the cradle mounting is not in use, the rotatable clamping jaws 24 are turned 25 inwardly toward each other or rearwardly as indicated by broken lines in Fig. 5. In mounting a drilling machine thereon, such as A, the front of the same is passed endwise through the loop 21 until the forward 30 guide lugs E or similar projections contact the loop. The rear of the machine is then dropped into place with the arms D' of the handle yoke on either side of the arms 22 of the cradle and with the through bolt heads B' seated in the sockets 23. The rotatable 35 clamping heads 24 are then swung to operative position above the bolt heads B' and are set up by tightening nuts 26, whereupon the mounting of the machine A is completed 40 and the same is ready for use.

In the modifications of the invention, disclosed in Figs. 5 to 9 inclusive, the engaging means for the rear of the drill are exactly the same as those shown in the first 45 modification disclosed in Figs. 1 to 4, and for this reason the same reference characters are used to indicate the same parts. In the form shown in Figs. 5, 6, and 7, the forward or left end of the cradle 16' has upwardly 50 disposed outwardly diverging arms 30 somewhat similar to arms 22 at the rear of the cradle. Arms 30, however, are shaped on their inner faces to conform substantially to the contour of the cylinder of the drilling machine, Fig. 7, and are formed with recesses 31 receiving the through bolts B and with sockets or recesses 32, Fig. 6, in which one of the forward guide lugs or projections E on each side of the machine is adapted to seat. A separate retainer 33 generally U-shaped in form cooperates with arms 30 to 55 retain the front of the machine in place. This retainer has parallel threaded ends 34 extending through vertical bores in those 60 portions of the arms 30 which project lat-

erally beyond the through bolts B of the drilling machine, nuts 35 being provided on ends 34 to secure the retainer in place. As indicated in Fig. 7, neither the arms 30 nor the retainer 33 make contact with the cylinder of the drilling machine, but the same serve as clamping jaws engaging the through bolts B. In this form of the invention the drilling machine is securely held in place by clamping means on the cradle engaging 70 spaced parts of the through bolts B, namely the bolt heads B' at the rear of the machine and the bolts B near the front.

Figs. 8 and 9 show alternative ways of securing the front of the machine to the cradle with any desired degree of rigidity. In Fig. 8 the forward engaging means on the cradle 16² comprises a yoke 36 hinged at 37 to bolt 38 in the vertical bore of one of the arms 30' and adapted to be held or locked in clamping engagement by headed bolt 39 in the vertical bore of the other arm 30' of the cradle by a nut 40 which serves to tighten or release the yoke 36. In this form of the invention, the arms 30' of the cradle and the hinged yoke 36 are arranged to fit the cylinder of the drilling machine as well as to engage the through bolts B.

In Fig. 9 the cradle 16³ has arms 30² in all respects similar to the arms 30' of Fig. 8. The vertical bores in these arms, however, are provided respectively with an eye bolt 42 and a hook bolt 43, each having nuts for setting up the same. Between the eye of bolt 42 and the hook of bolt 43 extends a 100 flexible connection such as a chain 44 which engages the cylinder of the drilling machine to retain it in place.

To mount a drilling machine on the cradle disclosed in Figs. 5 to 9 inclusive, it is necessary to displace the forward retaining means so that the drilling machine may be lowered into place while held parallel with the cradle. This permits the bolt heads B' to drop into recesses 23, the forward portions of the through bolts B into the recesses 31 in the arms 30, and the lower forward guide projections E into the sockets 32. The upper retaining member at the front is then moved into place, the U retainer 33 by passing the parallel ends 34 thereof through the co-operating bores in arms 30 and setting up the nuts 35, the hinged yoke 36 of Fig. 8 by swinging it into position and then applying and setting up nut 40, and the chain 44 of Fig. 9 by slipping it over hook 43 and then tightening up the nut on either the eye bolt 42, the hook bolt 43, or both. The rear of the drilling machine is made fast in the manner described in relation to the form of the invention shown in Figs. 1 to 4.

In the form of the invention first described the front end of the drilling machine is loosely held in the loop 21, which

permits the drilling machine to be removed with ease and speed since it is only necessary to loosen and swing the offset clamping heads 24 out of position to permit the rear of the drill to be raised and the front to be pulled out of loop 21. This loose mounting of the drill at the front has the further advantage of largely, if not entirely, eliminating side stresses on the mounting which result when crooked drill steels must be used or when crooked drill holes are encountered, a not infrequent occurrence in the actual practice of rock drilling. Lateral motion of the rear end of the drilling machine is permitted by the slight amount of clearance between the arms 22 of the cradle and the arms D' of the handle yoke.

As clearly indicated in the drawings, the handle yoke D abuts the forward faces of arms 22 of the cradle, thus transmitting the thrust of the drill to the cradle and thence to the supporting frame as the drill is advanced. The drilling machine is prevented from forward movement which might withdraw the bolt heads B' from the recesses 23 by the stops which cooperate with the forward guide lugs E of the drill, such as the loop 21 in the first form of the invention and the sides of the sockets 32 in the modified forms. The constructions illustrated in Figs. 8 and 9 provide for rigidly holding the drilling machine, while in the form shown in Figs. 5 to 7, wherein the machine is secured to the cradle by means of its side rods alone, a slight yielding of the drill in response to drilling conditions is possible dependent upon the resiliency of the through bolts B.

From the above it will be apparent that the device herein disclosed is adapted for the quick attaching or detaching of drilling machines and the like, that in using this device it is unnecessary to disturb in any degree whatever the assembly of the parts of the machine mounted thereon, that the machine is securely held for the purpose desired but play to a limited extent may be provided, and that various changes may be made in the form and arrangement of the parts to adapt the device to conditions of use and to various sizes and types of machines without departing from the inventive idea herein disclosed.

I claim:

1. The combination with a rock drilling machine having rearwardly projecting bolt head, of a feeding device comprising a movable cradle having engaging means for the front of the machine and a recess at the rear of said cradle for receiving said bolt head, and means for retaining said bolt head seated in said recess.

2. The combination with a drilling machine having a rearwardly projecting bolt head, of a feeding device comprising a mov-

able cradle having engaging means for the front of the machine and a recess at the rear of said cradle for receiving said bolt head and clamping means movable into and out of operative position for retaining said bolt head seated in said recess.

3. The combination with a rock drilling machine having rearwardly projecting bolt heads, of a feeding device comprising a movable cradle having engaging means for the front of the machine to prevent forward movement thereof and recesses at the rear of said cradle for receiving said bolt heads, and clamping means movable into and out of operative position for retaining said bolt heads seated in said recesses.

4. The combination with a rock drilling machine having rearwardly projecting bolt heads, of a feeding device comprising a movable cradle having engaging means for the front of the machine to prevent forward movement thereof and recesses at the rear of said cradle for receiving said bolt heads and clamping jaws rotatable into position above said bolt heads for retaining the latter seated in said recesses.

5. The combination with a rock drilling machine having through bolts, of a feeding device comprising a movable cradle having clamping means arranged to engage the through bolts of the machine to hold the machine upon the cradle.

6. In a device of the class described, in combination a supporting frame, a cradle thereon, means for moving the cradle relative to the frame, means at one end of the cradle for engaging a drilling machine provided with through bolts, and clamping jaws at the other end of the cradle for engaging the through bolts of the machine.

7. In a device of the class described in combination a supporting frame, a cradle thereon, means for moving the cradle relative to the frame, means at the front of the cradle for engaging a drilling machine provided with through bolts, and clamping jaws at the rear of the cradle for engaging the through bolts of the machine.

8. In a device of the class described, in combination a supporting frame, a cradle thereon, means for moving the cradle relative to the frame, and means adjacent the front and rear of said cradle for engaging a drilling machine supported thereon, said rearward engaging means fitting within the handle yoke of said machine and having clamping members arranged to cooperate with the heads of the through bolts of the machine.

9. In a device of the class described in combination a supporting frame, a cradle thereon, means for moving the cradle relative to the frame and means for detachably mounting a rock drilling machine on said cradle comprising clamping jaws at one end

and at each side of said cradle for engaging the through bolts of the rock drilling machine.

10. In a device of the class described in combination a supporting frame, a cradle thereon, means for moving the cradle relative to the frame and means for detachably mounting a rock drilling machine on said cradle comprising fixed clamping jaws at the rear and at each side of said cradle serving as positioning stops for the machine and engaged by the through bolts thereof, and movable clamping jaws associated with said fixed jaws for clamping the through bolts thereto, said movable jaws being rotatable out of operative position to permit quick mounting or removal of the machine.

11. In a device of the class described, a cradle upon which a drilling machine having rearwardly projecting bolt heads is adapted to be detachably mounted, longitudinally spaced supports on said cradle upon which portions of the machine may rest, the rearmost support providing recesses for said bolt heads and means associated with one of said supports for clamping the machine thereto.

12. The combination with a drilling machine having through bolts, of a feeding device comprising a movable cradle supporting the machine, said cradle having stop members engaging the machine at its front and rear ends and clamping means engaging the through bolts of the machine and associated with at least one of said stop members for securing the machine in place.

13. The combination with a drilling machine having through bolts, of a feeding device comprising a movable cradle supporting the machine, said cradle having a stop member having a forwardly opening recess receiving at least a portion of the rear end of the machine to prevent rearward movement thereof and clamping means engaging the through bolts of the machine adjacent the front end thereof for securing the machine in place.

14. In a device of the class described, a cradle upon which a drilling machine having rearwardly projecting bolt heads is adapted to be detachably mounted, longitudinally spaced supports on said cradle upon which portions of the machine may rest, the rear support providing recesses for said bolt heads and the front support providing

a stop to prevent forward movement of the machine relative to the cradle, and means for clamping the machine on the cradle.

15. In a device of the class described, a cradle upon which a drilling machine is adapted to be detachably mounted, said cradle having laterally extending parts engaged by the through bolts of the machine and means for clamping said bolts upon said parts.

16. In a device of the class described, a cradle upon which a drilling machine is adapted to be detachably mounted, having clamping jaws arranged to engage respectively the heads and the intermediate portions of the through bolts of the machine.

17. In a device of the class described, a cradle upon which a drilling machine is adapted to be detachably mounted, having pairs of clamping jaws arranged to engage respectively the heads and the intermediate portions of the through bolts of the machine, one jaw of each pair being movable out of operative relationship with the other jaw to permit quick mounting or removal of the machine.

18. In a device of the class described a movable cradle having recesses at one end adapted to receive the heads of the through bolts of a rock drilling machine, and clamping means arranged to engage other portions of the through bolts thereby firmly to hold said machine on said cradle while permitting its quick detachment therefrom when desired.

19. A cradle for supporting a drilling machine having through bolts on a feeding device, the cradle having a stop member arranged to fit within the handle yoke and providing forwardly opening sockets for the heads of the through bolts, and means in spaced relation to said member for clamping the machine to the cradle.

20. A cradle for supporting a drilling machine having through bolts on a feeding device, the cradle having a stop member arranged to fit within the handle yoke and providing forwardly opening sockets for the heads of the through bolts, and clamping means engaging said machine in spaced relation to said member and serving as a stop against forward movement of said machine.

Signed by me at Detroit, Mich., this 27th day of June, 1923.

ERNEST PENBERTHY.
